UNITED STATES PATENT OFFICE

107,165

DESIGN FOR A DRESS

Philip Wenett, New York, N. Y.

Application October 25, 1937, Serial No. 72,401

Term of patent 3½ years

To all whom it may concern:

Be it known that I, Philip Wenett, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The circular elements on the dress, as shown, represent rhinestones.

I claim:

The ornamental design for a dress, substantially as shown, and described.

PHILIP WENETT.
